GEORGE STANFORD WITHAM, JR., OF HUDSON FALLS, NEW YORK

PULPING MACHINE

Application filed January 24, 1928, Serial No. 249,064. Renewed April 4, 1930.

My invention relates to pulping and disintegrating and particularly to a modification of the machine for performing these processes described in my copending application, Serial No. 239,965, filed Dec. 14, 1927. It relates to a machine for breaking up and pulping hard materials such as baled pulp, old news or board stock kraft, sulphite and ground wood sheet or lap stock, or the like, and thus preparing the material for further treatment. It relates particularly to improvements and modifications in the apparatus described in the above mentioned application whereby the construction and operation are greatly simplified.

The present practice in breaking up hard stock preparatory to subjecting it to further treatment, is to first cut the material into short shreds by feeding it against revolving knives in what is termed a shredder. The shredded stock is then mixed with water in a suitable chest, and the mixture delivered to the beaters as required. The stocks which are now being delivered to the mills are bone dry and hard, and shredding in this way not only requires a great deal of hand labor, and an excessive amount of power, but the action of the knives cuts rather than separates the fibers so that many of them are rendered too short for the purpose for which they are intended. Moreover, because of being shredded in a bone dry state, a great deal of dust is created thus increasing the fire hazard about the mill.

Machines of the type described herein and in application Serial No. 239,965 perform the disintegrating and pulping operation in a somewhat different way. By the use of my machines the individual fibers are preserved substantially intact, and the disintegration and hydration of a mass of material, regardless of its bulk, is carried on simultaneously.

The objects of my invention, generally, are to provide an apparatus for breaking up and pulping hard materials with a minimum of power and labor. Another object is to provide an apparatus whereby the pulping of such materials may be conducted on a comparatively large scale, and whereby the operation may be made a substantially continu-

ous one. Another object is to provide an apparatus whereby hard materials are disintegrated and simultaneously mixed with water, whereby a continuous flow of prepared material from the pulper may be maintained. 55 A further object is to provide an apparatus whereby the particles of stock in the resulting pulped mixture may be limited to a definite maximum size, and in which the consistency of the mixture may be controlled to a considerable extent. And a still further object is to provide an apparatus of this character which is extremely simple in construction and which may be built of any size and capacity whatsoever. 65

In the device described in my application Serial No. 239,965, I propose to use a foraminous drum rotated in a tank of water. In the device herein described, I propose to eliminate the tank by using the drum itself as 70 a container for the water, and to discharge the pulped material through openings in the end rather than the side of the tank.

With these objects in view, my invention includes the novel elements and the arrangements and combinations of elements described herein and illustrated in the accompanying drawings in which—

Fig. 1 is a side elevation in partial section of my machine with portions thereof broken away to show the interior construction;

Fig. 2 is a half-section in the plane 2—2 of Fig. 1;

Fig. 3 is a side elevation in partial section of a slightly modified type of machine having 85 portions thereof broken away to show the interior construction;

Fig. 4 is a half-section of Fig. 3 in the plane 4—4;

Fig. 5 is a view of the right hand end of 90 the machine shown in Fig. 1; and

Fig. 6 is a fragmentary view of a modified form of baffle.

Referring particularly to the drawings, my invention comprises a drum, 1, preferably but not necessarily cylindrical in shape, and mounted to rotate with its axis substantially horizontal. This drum may be of any desired size, and preferably is rather large—say ten or more feet in diameter and thirty 100

or more feet in length—the dimensions of any specific drum depending upon the character of the material to be pulped and the capacity desired. This drum, as illustrated, comprises an imperforate cylindrical plate, 2, having ends or heads, 3 and 4. The interior surface of the cylinder is provided with inwardly projecting elements, 5, which may comprise angles riveted to the interior of the cylindrical plates, as shown, thus forming radial baffles extending longitudinally of the drum. These baffles or projections may vary in size and character depending upon the materials to be pulped, and their function in some cases may be merely to provide a "roughened" interior, and in other cases to provide pockets within which some of the material to be pulped will be carried upwardly as the drum rotates and dropped downwardly into the drum from points above the bottom. These baffles, if desired, may be serrated as shown in Fig. 6 to facilitate the disintegration of the material to be pulped.

Referring particularly to Figs. 1 and 2, the head or end, 3, is provided with a comparatively large hollow shaft, 6, fitted in a suitable bearing 7. This shaft should be of sufficient diameter to permit the introduction therethrough into the drum proper of comparatively large masses of materials, such as bales of pulp or the like. This material may be introduced into the drum by means of a conveyor, 8, discharging into the hollow shaft, 6. The bearing for the shaft may be of any type, although it will be found convenient to support the shaft upon rollers, 9, as shown in Fig. 5. These rollers are in turn supported in bearings, 10, and adjusting screws, 11, are provided whereby the bearings may be properly aligned.

In the type shown in Fig. 1, the delivery end of the machine is provided with an axial shaft, 12, supported in a suitable bearing, 13, which should be adapted to take any horizontal thrust arising from the introduction of the materials. The shaft, 12, is connected to a worm type reduction gear, 14, through the flexible coupling, 15, and the reduction gear is in turn driven by a suitable motor. Depending somewhat upon the material to be pulped, and the depth of water to be maintained in the drum, the head, 4, is perforated as shown in Fig. 2. If a depth of 12 inches of water is to be maintained in the cylinder, the outer circular row of holes or perforations, 16, is located 12 inches from the interior of the drum, and other rows of perforations, 17 and 18, for example, may be provided as shown.

At the delivery end of the machine is a trough, 19. The bottom of this trough may be provided with a screw conveyor, 20, driven from a suitable source of power, not shown, which will force the material falling into the trough toward one end thereof and cause it

to flow downwardly into the discharge pipe, 21.

In the type of machine shown in Fig. 3, I have provided the discharge end with a hollow shaft, 22, of somewhat larger diameter than the shaft, 6, at the delivery end. This shaft may be supported on a roller bearing, 7, similar to the bearing, 7, at the charging end. In this type, the rollers, 9, may be provided with flanges adapted to embrace the sides of hardened metal rings, 23, surrounding the shafts, 6 and 22, respectively, so that any horizontal thrust may be taken care of in this way. The diameter of the opening in shaft, 22, may be, for example, two feet less than the interior diameter of the drum so that a twelve inch depth of water is maintained within the drum. The discharge passage through hollow shaft, 22, is provided with a screen or perforated plate, 24, adapted to regulate the maximum size of the particles of material which can pass therethrough. This screen obviously need not be at the inner end of the shaft, 24, and could be at the outer end or at any intermediate point. The drum shown in Fig. 3 may be rotated by any suitable means, and merely for the purpose of showing some method of driving I have illustrated a sprocket, 25, around the center of the drum so that it may be driven by a chain running to a suitable source of power.

Some means of furnishing a continuous supply of water to the interior of the drum must be provided, and for this purpose, I have shown a pipe, 26, extending through the shaft, 6, and opening within the drum. To regulate the flow of water, a valve, 27, is placed at some convenient point in the pipe line.

In the operation of my device, the materials to be pulped are introduced into the drum through the hollow shaft, 6. The supply of water is regulated by means of the valve, 27, and the materials are tumbled about in the drum as it rotates. This procedure subjects the materials to abrasion or shock or to both abrasion and shock depending upon the character of the projections or baffles, 5. As the materials are tumbled about in the drum they are broken up and disintegrated and the smaller particles thereof are carried out through the perforations in the discharge end of the drum. In the type shown in Fig. 1, the pulped material falls directly into the trough, 19, and is carried away by the screw conveyor, 20. In the type shown in Fig. 3, the material flows out through hollow shaft, 22, and into the funnel-like end, 28, of pipe, 29.

In many instances it may be found desirable to tumble the materials in the presence of masses of a less mutable material. Where this is the case, stones, such as hard heads, blocks of hard wood, or masses of metal covered with rubber, may be introduced into the

cylinder. These masses are introduced into the drum through the charging end and in many cases will facilitate the disintegration of the material by the additional pounding and abrasion effects obtained by their presence.

The maximum size of the particles of pulped material may be controlled by varying the size of the screen openings in the discharge end of the drum, and the consistency of the mixture may be controlled to some extent by regulating the supply of water delivered to the drum. The device requires substantially no attention from an operator and no preliminary treatment of the raw material is necessary. Raw material in bales, bundles or other form is fed into the charging end and a continuous supply of pulped material is delivered from the other end of the machine.

While I have described my invention in its preferred embodiment, it is to be understood that the illustrations are purely typical, that the words which I have used in describing my invention are words of description rather than of limitation, and that changes within the purview of the appended claims may be made without departing from the true scope and spirit of my invention in its broader aspects.

What I claim is—

1. A pulping machine comprising a rotatively mounted, substantially horizontal drum having imperforate sides and provided, at one end, with a hollow shaft of a diameter adapted to admit to said drum large masses, such as bales or laps, of material to be pulped, the opposite end of said drum being perforated in a zone intermediate the periphery and axis but imperforate throughout a zone of substantial width adjacent the periphery; the maximum diameter of the perforate zone exceeding the interior diameter of said hollow shaft.

2. A pulping machine comprising a rotatively mounted, substantially horizontal cylinder having imperforate sides and provided with a hollow axial shaft at either end, one of said shafts being of a diameter adapted to admit to said drum large masses, such as bales or laps, of material to be pulped, and the other shaft being of somewhat larger interior diameter, means for introducing water into said cylinder, and a screen intermediate the cylinder and larger shaft adapted to limit the size of the pulp particles discharged from the drum.

3. A pulping machine comprising a rotatively mounted, substantially horizontal cylinder having imperforate sides and provided, at one end, with a hollow axial shaft of a diameter adapted to admit to said cylinder large masses, such as bales or laps, of material to be pulped, the opposite end of said cylinder being imperforate throughout

a zone of substantial width adjacent the periphery but perforate intermediate said zone and the axis of said cylinder; and means for maintaining a continuous flow of water through said cylinder.
